(57) **CLAIM**

The ornamental design for a solar LED lamp, as shown and described.

DESCRIPTION

FIG. 1 is a perspective view of a solar LED lamp showing our new design;

FIG. 2 is a front elevational view thereof;

FIG. 3 is a rear elevational view thereof;

FIG. 4 is a left-side, elevational view thereof;

FIG. 5 is a right-side, elevational view thereof;

FIG. 6 is a top plan view thereof; and,

FIG. 7 is a bottom plan view thereof.

The structure shown in broken lines represents environment only and forms no part of the claimed design.
